UNITED STATES PATENT OFFICE.

ERNEST SHERWOOD ASTIN, OF BALTIMORE, MARYLAND, ASSIGNOR TO THE LIBERTY TOOL COMPANY, OF BALTIMORE, MARYLAND, A CORPORATION OF MARYLAND.

BACKING-OUT PUNCH.

1,362,911.

Specification of Letters Patent. Patented Dec. 21, 1920.

Application filed September 15, 1919. Serial No. 323,752.

To all whom it may concern:

Be it known that I, ERNEST S. ASTIN, a citizen of the United States, and resident of Baltimore, Maryland, have invented certain new and useful Improvements in Backing-Out Punches, of which the following is a specification.

The invention is for use with pneumatic hammers and relates to a backing out punch for driving rivets out of holes in dismantling any riveted structure.

It consists of the features and combination of parts hereinafter described and particularly pointed out in the claim.

15 In the accompanying drawings,

Figure 1 is a view of a pneumatic hammer with my improvement combined therewith.

Fig. 2 is a view of the punch detached, and

Fig. 3 is a view of the bushing.

20 In these drawings 1 indicates a pneumatic hammer of ordinary form, 2 indicates a backing out punch, and 3 indicates a bushing which externally is of cylindrical form to fit a recess 4 formed in the interior of the

25 end portion of the hammer barrel pressing a shoulder 5 against which the bushing is seated. This bushing has a conical opening tapering toward the inner side of the hammer barrel and this tapered opening provides a seat for receiving the shank 6 of the punch 2 which shank is tapered to fit the conical seat of the bushing. The punch also tapers from its central part 7 toward its front end 8.

30 Backing out punches as heretofore constructed have been made with a tapered

front end, a shank of cylindrical form and a main central body portion of greater diameter than the shank providing a shoulder intermediate the shank and the body portion. 40 This old form of backing out punch is liable to breakage particularly at the intermediate shoulder and at points along its tapered front end. This breakage is due to the crystallization of the metal resulting from 45 the rapid blows delivered by the punch. With my improvement there is no abrupt shoulder between the fore part of the punch and its shank portion, but a long bearing face is provided between the points α and β , 50 this bearing face being tapered and accurately fitting along the tapered seat within the bushing 4 so that the strain resulting from the force of the blows will be distributed along this face and taken by the 55 bushing, which being surrounded by the wall of the hammer barrel throughout its length, will resist any breaking tendency and the thrust will be taken by the shoulders 5 within the hammer. 60

I claim as my invention:

A backing out punch for use with pneumatic hammers comprising a punch member tapered from its central portion all the way to its front and rear ends and a bushing having an opening tapered throughout providing a seat for the tapered shank portion of the punch member or the tapered front part when the punch is reversed, substantially as described. 65

In testimony whereof I affix my signature.
ERNEST SHERWOOD ASTIN. 70
